US00D698263S

(12) **United States Design Patent**
Anastasiadis et al.

(10) **Patent No.:** **US D698,263 S**
(45) **Date of Patent:** **** Jan. 28, 2014**

(54) **FLEXIBLE CONTAINER**

(71) Applicant: **Reckitt Benckiser LLC**, Parsippany, NJ (US)

(72) Inventors: **John Anastasiadis**, Tinton Falls, NJ (US); **David Adam Demar**, Tenafly, NJ (US); **Andrew Campbell**, Maplewood, NJ (US); **Thomas C. Van Dyk**, Ramsey, NJ (US); **Jeffrey Gibb**, Randolph, NJ (US); **Arti Shah**, Wayne, NJ (US); **Brian Young**, Dobbs Ferry, NY (US); **Lindsay Ann Mathisen-McDonald**, Parsippany, NJ (US); **Marjorie Van Derlaan**, Long Valley, NJ (US)

(73) Assignee: **Reckitt Benckiser LLC**, Parsippany, NJ (US)

(**) Term: **14 Years**

(21) Appl. No.: **29/435,343**

(22) Filed: **Oct. 23, 2012**

Related U.S. Application Data

(63) Continuation of application No. 29/420,995, filed on May 15, 2012, now abandoned, which is a continuation-in-part of application No. 29/418,788, filed on Apr. 20, 2012, now abandoned.

(57) **CLAIM**

The ornamental design for a flexible container, as shown and described.

DESCRIPTION

FIG. 1 is a front and side perspective view of our flexible container;

FIG. 2 is a front elevational view thereof;

FIG. 3 is a rear elevational view thereof;

FIG. 4 is a left side elevational view thereof, the right side being a mirror image thereof;

FIG. 5 is a right side elevational view thereof;

FIG. 6 is a top plan view thereof; and,

FIG. 7 is a bottom plan view thereof.

The features shown broken lines in the drawings are for the purpose of illustrating environmental structure, and form no part of the claimed design.

1 Claim, 4 Drawing Sheets
